UNITED STATES PATENT OFFICE.

NELS H. WHEELER AND NEIL M. NEWHOUSE, OF CORVALLIS, OREGON.

DEVICE FOR SWAGING INSERTIBLE SAW-TEETH.

SPECIFICATION forming part of Letters Patent No. 425,196, dated April 8, 1890.

Application filed October 25, 1888. Serial No. 289,135. (No model.)

To all whom it may concern:

Be it known that we, NELS H. WHEELER and NEIL M. NEWHOUSE, of Corvallis, in the county of Benton and State of Oregon, have 5 invented a new and Improved Device for Swaging Insertible Saw-Teeth, of which the following is a full, clear, and exact description.

This invention relates to saw-swaging devices, the object of the invention being to improve the swaging device illustrated, described, and claimed in Letters Patent of the United States No. 364,877, granted to us on the 14th day of June, 1887.

The features of the improvement are as 15 hereinafter described and claimed.

Reference is to be had to the accompanying drawings, forming a part of this specification, in which similar figures and letters of reference indicate corresponding parts in all the 20 views.

Figure 1 is a face view of my improved device for swaging insertible saw-teeth, parts being broken away. Fig. 2 is a cross-sectional elevation of the device; and Fig. 3 is a 25 perspective view of the swage-block, the adjustable die-blocks being shown in position.

In the drawings, 10 represents the stock or standard of the machine, the upper end of which stock is slotted to receive the swaging- 30 lever 11, which lever is made integral with or rigidly connected to a pointed operating-cam 12, the point or angle of said cam being shown at *a*. A swage-block 13 is held against the standard 10 by a bolt 14, which bolt 35 passes through an elongated vertical slot *b*, that is formed through the body of the stock or standard, and in order that the swage-block may be properly guided we form said block with side ribs or flanges 15, which overlap a central rib 16, that extends outward from the stock or standard 10. A shoulder 17 extends outward from the rib 16, and this shoulder serves as the bed or support for adjusting-wedges 18, which serve to rigidly 40 support the swage-block in any desired position, as will be hereinafter more fully explained.

In the upper face of the block 13 there is a recess, in which are fitted die-blocks 20 and 50 21, the die-block 20 being formed with a central recess *c*, formed with a curved defining-

wall, against which the curved face *d* of the saw-teeth 30 rests, while the die-block 21 is formed with a bearing-face *e*, arranged to support the flat exposed end of the saw-tooth. 55

In order that the blocks 20 and 21 may be adjusted so as to operate properly in connection with saw-teeth of different sizes, we provide a set-screw 22, which passes through a portion of the swage-block 13 in position 60 such that the forward end of the screw may be brought to bear against the side face of the block 20 and bind it firmly to any position to which the block may be adjusted, while the block 21 may be adjusted as to height 65 by placing a washer beneath the block, as will be readily understood.

To hold the saw-tooth firmly in position when it is being swaged, we provide a clamping arm or lever 23, which is loosely connected to one side of the swage-block and arranged so that it may be thrown across the face of the upper die-block, there to enter the recess formed in the forward face of the saw-tooth. (See Fig. 1.) 70

To adjust the block 13, the nut of the bolt 14 is loosened, the block moved to a proper position, the wedges 18 being adjusted beneath the block, so as to properly support it, after which the nut of the bolt is tightened 80 to hold the block against accidental displacement, and the block 13 having been properly adjusted, the die-blocks 20 and 21 are adjusted to suit the requirements of the saw-teeth that are to be swaged. Then as the lever 11 is moved in the direction of its arrow 85 the cam 12 will be brought to bear against the tooth 30 and will act thereon until the point *a* has passed the tooth, the lever dropping somewhat beyond the position in which 90 it is shown in dotted lines in Fig. 2. By this arrangement we provide for a uniform action upon all teeth operated upon.

In order that the saw-tooth may be spread as well as drawn, we make the operating cam-face convex. 95

Having thus described our invention, we claim as new and desire to secure by Letters Patent—

1. As an improvement in devices for swaging insertible saw-teeth, the improved means hereinbefore described, to wit: the die-block, 100

a die mounted thereon, and the swaging-lever having its face provided with point α , as shown and described.

2. In a saw-swaging device, the combination, with a stock or standard, of a swage-block adjustably held thereto, dies adjustably supported by the swage-block, a swaging-

lever, and a tooth-holding bar, substantially as described.

NELS H. WHEELER.
NEIL M. NEWHOUSE.
